(57) **CLAIM**

The ornamental design for a pot body, as shown and described.

DESCRIPTION

FIG. 1 is a front elevation view of a pot body, showing our new design;

FIG. 2 is a back elevation view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines in the figures depict portions of the pot body that form no part of the claimed design. The shade lines in the figures show contour and not ornamental surface ornamentation.
